CLAIM

The ornamental design for a medical article, as shown and described.

DESCRIPTION

FIG. 1 is a perspective view of a medical article showing the new design;

FIG. 2 is a top plan view thereof;

FIG. 3 is a bottom plan view thereof;

FIG. 4 is an end view thereof; and,

FIG. 5 is a side view thereof.

The broken lines in the figures are for illustrative purposes only and do not form a part of the claimed design.
